UNITED STATES PATENT OFFICE.

ARNOLD STUCKI, OF PITTSBURGH, PENNSYLVANIA, ASSIGNEE OF ONE-HALF TO
PETER M. KLING, OF PITTSBURGH, PENNSYLVANIA.

BOX-CAR.

1,137,922.

Specification of Letters Patent.

Patented May 4, 1915.

Application filed August 12, 1908. Serial No. 443,232.

To all whom it may concern:

Be it known that I, ARNOLD STUCKI, a resident of Pittsburgh, in the county of Allegheny and State of Pennsylvania, have invented a new and useful Improvement in Box-Cars, of which the following is a specification.

This invention relates to railway car construction, and more particularly to the construction of the ends of box, baggage, express, and similar cars.

The object of the invention is to provide a construction of this character comprising a self-contained metal frame which provides a maximum of strength together with lightness of construction, and is able to stand the strain of shifting loads.

The invention comprises the construction and arrangement of parts hereinafter described and claimed.

In the accompanying drawings Figure 1 is in part an end view of the car and in part a view of the end framing with the end sheathing removed; Fig. 2 is a plan view 25 of a part of the car underframe on an enlarged scale; Fig. 3 is a vertical central longitudinal section of the car end; and Figs. 4, 5, 6, 7 and 8 are detail views of various parts of the structure.

The underframe of the car may be of any desired construction. The one illustrated has been selected merely as one type which can be used for this purpose. The underframe shown is designed to carry practically 35 the entire load on the center sills, these being in the form of plate girders 1, tapering toward their ends, and at their upper edges being provided with a single angle bar 3. The two center sills are connected by a top 40 cover plate 4 riveted to the angle bar 3. These center sills shown may project entirely to the ends of the car. Preferably, however, to facilitate repair, said sills project only slightly beyond the body bolsters 45 and have spliced thereto the draft sills 6, which are shown as pressed members of general Z shape in cross section. The body bolsters comprise center fillers or braces 7 between the center sills, and web members 8 extending from the center sills out to the car sides. These web members are pressed members with flanges on all edges, the inner flanges being riveted to the center sills. Two such web members are provided placed back to back. A bottom cover plate 9 is

riveted to the bottom flanges of the web members 8, and central braces 7, said cover plate extending uninterruptedly from side to side underneath the center sills. A top cover plate 10 is similarly riveted to the top 60 flanges of the web members 8, and extends across the center sill cover plate 4.

The corner posts 30 are of general channel shape, being secured at their upper ends to the end carline or end roof angle of the car 65 31, and at their lower ends being secured to the end sill 33. The end sill is composed of two sections extending from the draft sills to the corners of the car. The end sill is of channel shape with the web arranged vertically and is also provided with end flanges. The bottom flange of the end sill, at the corners of the car, is turned into the plane of the web, as indicated at 34, to give an enlarged riveting area at this point. A 75 bottom side angle 35 is secured to the lower end of the side posts and also to the corner posts. Push-pole pockets 36 are secured over the joint of the end sill, corner posts and side angle 35, giving a finish at this 80 point and also adding strength to the connection.

The end wall is made very strong so as to take care of the shocks due to the shifting loads, being braced and trussed to effectively 85 take care of the stresses. It is provided with end posts 37 of general channel shape with the webs arranged longitudinally of the car and being much wider at their lower ends than at their upper ends. The inner flange 90 of these posts at the bottom is turned into the plane of the web, as shown at 38, Figs. 2 and 3, to provide an enlarged riveting area for riveting to the web of the draft sills. These posts taper toward their tops, and 95 their upper ends lie inside of the vertical flange of the end roof angle 31. The flange 39 at the inner end of the end sill 33 is secured to the web of an end post, while the flange 40 at the end of the end sill is riveted 100 to the web of a corner post, side angle 35, and push-pole pocket 36. Diagonal braces 42 extend from the lower ends of the end posts 37 to the upper ends of the corner posts 30. These braces are of angle shape, 105 and have their lower ends bent to horizontal position, as at 44, and riveted to the top flange of the end sill and then bent upwardly, as at 43, and riveted to the webs 110 of the end posts. These braces serve to keep

the car body square, form connections and braces between the end sills and the end posts, and also form stops for shifting loads, having their lower ends near the center of the car body so as to effectually take care of such stresses. The upper ends of the braces 42 fit into the upper ends of the corner posts 30 and are riveted thereto. Side truss rods 46 of the car preferably have their ends extending through these overlapping corner posts and braces, and anchored therein.

The end portion of the car underframe is provided with diagonal braces 48, which are of general trough shape to receive a nailing strip 49. The ends of these braces are flattened out to provide wide riveting areas for attachment at their inner ends to the cover plates of the body bolster and center sill, and at their outer ends for attachment to the end sill and side angle. At their inner end one side of the trough shape brace 48 is depressed, as at 50, to form a seat for a nailing strip 51, while at the outer end the other side of said brace is likewise depressed, as at 52, to provide a seat for the nailing strip 53. Between the outer ends of the draft sills is a casting 55, which is recessed from its lower edge to receive the shank 56 of the coupling. This casting is riveted to the draft sills, and is provided with an upwardly projecting flange or flanges 62 for the attachment of the end sheathing.

The car frame described is adapted to receive sheathing, roof, floor and lining of any desired character. As shown, the car is provided with a wooden floor 64, nailed to the stringers and nailing strips described, and a wooden spring 65 which may extend upward to any desired height and is nailed to suitable wooden nailing strips 66 secured to side posts of the car and to the corner and end posts. The external sheathing and car roof may likewise be of wood if desired, but preferably are formed of metal. The side sheathing is formed of sections of sheet metal, 67, extending from top to bottom and having their side edges joined by suitable interlocking flanges 68. The sections comprising the sheathing are assembled on the ground with the interlocking flanges and are riveted through the flanges as necessary or desired. The roof is composed of similar sheet metal sections 69 provided with similar interlocking flanges 70. The ends of the roof sheets are riveted to the side roof or eave angle 71. In erecting the car, the side angle 35 is slightly spaced from the outer edges of the side posts and the outer ends of the floor cross members. The assembled side sheathing is then applied bodily, the lower edges of said sheathing being inserted inside of the side angle 35. If desired, the side sheathing of the car may be applied to the outside of the side angle 35 by flattening

the interlocking flanges of said sheathing, but it is preferred to apply the sheathing inside the angle 35, as said angle forms a protection against injury from the wheels of wagons which back against the car when loading and unloading. The roof sheathing likewise is self-contained and is applied bodily, the eave angles 71 fitting over the top edges of the side sheathing. The members are then riveted together at the top and bottom and at the posts.

The flanges 70 of the roof sheets preferably project upwardly or outwardly and form transverse ribs to stiffen and strengthen said roof. Cleats for the running board 73 may be secured directly to these flanges when projecting outwardly.

The end sheathing is made in sections. Between the end posts 37 the metal sheet 78 is provided with edge flanges riveted to the webs of the end posts. Centrally this sheet is provided with a vertical corrugation to stiffen the same. Its upper end lies inside of the end roof angle 31, and its lower end is riveted to the flange or flanges 62 of the end casting 55. Between the end and corner posts the end sheathing is made up of sections 79, and joined together by interlocking flanges 68, like the side sheathing, and with the flanges projecting inwardly. At the inner edge, the sheathing is flanged and riveted to the web of an end post. The upper edge lies inside of the roof angle, and the lower edge can be riveted to the outer face of the end sill.

The car section described comprises an all metal frame adapted to effectively take care of all loads and stresses, and adapted to receive sheathing, roof, floor and lining of any character.

What I claim is:

1. A railway box car comprising central longitudinal sills, a roof, roof carlines, and end posts riveted to the sills and to the end carlines, said end posts being of channel section extending downwardly below said rivets with undiminished width and tapering toward their tops.

2. A railway box car comprising central longitudinal sills, a roof, roof carlines, and end posts of channel form tapering toward their tops, having their webs riveted to the webs of the longitudinal sills and their upper ends riveted to the end carlines, said posts extending downwardly of undiminished width below the rivets which secure the same to the longitudinal sills.

3. A railway car frame comprising central longitudinal sills, roof carlines, and end posts riveted to the ends of the sills and the roof carlines, said posts being of channel form and having their inner flanges at the bottom turned into the plane of the webs to provide enlarged riveting areas.

4. A railway car frame comprising central

longitudinal sills, end posts secured to said sills, a divided end sill, and diagonal braces secured to the inner ends of the sections of the end sills and extending to the upper

secured to the corner posts and their lower ends provided with a horizontal portion secured to the end sill and a vertical portion 35 secured to an end post.

5 outer corners of the car.

5. A railway car frame comprising central longitudinal sills, a divided end sill, a car body, end posts riveted to the ends of the central sills, and diagonal braces secured to the lower ends of said end posts and 10 extending to the upper outer corners of the car body.

6. A railway car frame comprising central longitudinal sills, a roof, an end roof 15 carline bent to conform to the contour of the roof, and end posts riveted to the ends of the central sills and tapering toward their upper ends and secured to said end roof carline.

20 7. A railway car frame comprising central longitudinal sills, end posts secured to said sills, a divided end sill, and diagonal braces secured to the end sill and end posts.

8. A railway car frame comprising central longitudinal sills, end posts secured to said sills, an end sill, corner posts, and diagonal braces secured at their lower ends to the end sill and end posts and at their upper ends to the corner posts.

25 9. A railway car frame comprising end sills, end posts, corner posts and diagonal braces, said braces having their upper ends

secured to the corner posts and their lower ends provided with a horizontal portion 40 secured to the end sill and a vertical portion end sill and having their upper ends secured to the corner posts near the top.

10. A railway car frame comprising longitudinal sills, end posts secured to said sills, an end sill, corner posts secured to the end sill, and diagonal braces extending from the 45 end sill and having their upper ends secured to the corner posts near the top.

11. A railway car frame comprising corner posts, diagonal end braces having their upper ends lapping the upper ends of the 45 corner posts, and side truss rods anchored in said overlapping ends.

12. A railway car frame comprising corner posts and end sills riveted together, said end sills being of channel form with the 50 lower flange at the corners turned into the plane of the web to provide enlarged riveting areas.

13. A metal railway car comprising draft sills, metallic end sheathing, and a casting 55 riveted between the ends of the draft sills and provided with an upwardly projecting flange secured to the end sheathing.

In testimony whereof, I have hereunto set my hand.

ARNOLD STUCKI.
